PRINTING CONTROL MECHANISM

Hermann, Adalbert Weinlich, Berlin-Charlottenburg, and Ulrich Kölz, Berlin, Germany, assignors, by mesne assignments, to International Business Machines Corporation, New York, N. Y., a corporation of New York

Application July 5, 1929, Serial No. 376,142
In Germany January 26, 1929

5 Claims. (Cl. 235—92)

The invention relates to accounting machines and particularly to the printing mechanism for such machines and has for its principal object the provision of a novel form of character suppression mechanism.

The system, while not limited to such use, finds particular application to automatic tabulators which add and print items derived from perforated record cards and will be explained in connection with an electrical machine of this type. The numbers are represented on the record cards by perforations arranged in vertical columns each column pertaining to a denominational order. The digits from 0 to 9 are represented by perforations in the columns which perforations are progressively displaced according to the particular digits which they represent. Ordinarily a digit in the lowermost position represents 9, one in the next higher represents 8 and so on. The cards are fed with a steady motion beneath electrical brushes in the tabulator, one brush being provided for each card column, and each brush, as it encounters a perforation, causes a timed impulse whose timing corresponds to the value of the digit represented by the perforation. These impulses operate counter and printer magnets whereby the number represented on the card may be added and printed.

It is common practice in subtracting numbers by accounting machines to add the complementary value of the subtrahend. In the present case it will be assumed that this is done by punching the complementary value of the subtrahend directly on the record and as ordinarily the nine complement of the subtrahend is used and an additional unit entered into the units column to obtain the true complement it will be assumed that the nine complement is punched on the card and the additional unit entered in one of the well known manners, for example as in the British Patent No. 273,731.

It has been suggested, in dealing with complements, as for example in the British Patent No. 304,383, that the type on the usual type bar be inverted in order that, when a complementary value is entered on the accumulating mechanism, the true value corresponding to it will be printed. Thus when a nine perforation occurs on a record the printing mechanism will function to print zero, an eight perforation causes printing of one and so on. In such a case it is desirable to suppress the printing of zeros to the left of the first significant figure and it is the prime purpose of

the invention to provide a zero suppression system adapted to such a printing mechanism.

In tabulating work every column of the record cards is punched and hence printing must be suppressed from all perforations which tend to print zeros to the left of the first significant figure of a number. The usual method is to suppress zero printing from record cards entirely and control the printing of zeros which occur to the right of the first significant figure from the adjacent left hand type bars which print significant figures.

The invention is illustrated by way of example in the accompanying drawings in which:

Fig. 1 is a diagram illustrating the relative arrangement of the index point position on the control card and the type on the type bar for complementary printing;

Fig. 2 is a schematic circuit diagram of a tabulating machine with zero suppression according to the present invention;

Fig. 3 is a view of the accumulator showing a plurality of accumulating elements;

Fig. 4 is a view of the printing mechanism showing a plurality of type bars and printing magnets;

Fig. 5 is a time chart representing diagrammatically the timing of two of the cam controlled contact devices.

The circuit diagram illustrated in Fig. 2 is that of a standard tabulator of well known type such as shown in the patent to Bryce No. 1,702,628, dated February 19, 1929 but as the present invention relates only to character suppression in a certain portion of the mechanism only those parts which directly concern this portion of the mechanism have been shown. Referring to Fig.

1, the record card A moves downwardly in the direction of the adjacent arrow to bring its index point positions successively under the brushes B. The type bar T, which is coordinated with a record column moves upwardly as indicated by its arrow in synchronism with the card movement so that each type slug on the bar passes printing position opposite the platen P as its corresponding complementary index point position on the record card is passing under the brushes B. As it has been assumed in the present case that nine complements are to be recorded on the record card but that the true values are to be printed the type slugs are reversed in order, so that the zero type passes printing position as the nine index point on the record passes the analyzing brushes B. Whenever the brushes B encounter a perforation an electromagnet interrupts fur-

ther movement of the type bar leaving the proper type in position for printing. In the present case the zero type which must be suppressed is uppermost on the bar and therefore presents a special 5 problem in suppression.

Referring to Fig. 2 the usual driving motor for operating the machine during tabulating or adding is shown at TM and this is controlled by circuits and relays indicated at C so that perforated 10 record cards pass the lower brushes LB successively to have their perforations analyzed. Whenever a brush encounters a perforation a timed impulse flows through a counter magnet Z serving to enter the corresponding number on a counter 15 wheel. Several such magnets Z have been shown and each is distinguished by a different subscript after the letter Z. Where the description refers to a letter without an accompanying subscript, it includes the several orders; viz. reference to 20 magnet Z applies to Z₁, Z₂, Z₃ and Z₄. The magnet Z₁ also causes contact z₁ to open, breaking its circuit to prevent sparking at the brushes, and contacts s₁ to close. The latter establish a circuit for the printing magnet S₁ which interrupts 25 the motion of the type bar as previously explained and holds the proper type in printing position. This mechanism is well known in the art and is therefore but briefly described here. For fuller explanation, reference may be had to Patent No. 30 1,307,740, issued June 24, 1919 to C. D. Lake in which the elements 2, 1 and 13 correspond to the elements LB, Z and z respectively. Patent No. 1,822,594, issued September 8, 1931 to C. D. Lake, corresponding to British Patent No. 216,142, also 35 discloses in greater detail elements LB, Z, z and s which correspond to elements 59, 98, 99 and 100 in that patent. Reference may also be had to Patent No. 1,534,531, issued April 21, 1925 to C. D. Lake. In the present case, of course, this 40 type represents the true value of a complementary number on the record card and adding element.

It will be noted that the zero type on the bars pass printing position first so that if zero suppression is to occur it must become effective from the beginning of the cycle while if a zero is to be printed it must likewise be selected at the beginning of the cycle. A relay R₁ is wired in parallel with the printing magnet and in series with 45 cam contacts 17 which close only at the nine index point position, which in the present case corresponds to the zero position of the type bar. This relay is provided with contacts r₁ and contacts t₁, the contacts r₁ being in the circuit of the corresponding printing magnet S₁ and the contacts t₁ forming an additional circuit for this magnet through the contacts r₂ of the next higher denominational order. All the print magnets S have a 50 common return circuit 15 including cam contacts 16, which are normally closed, but which open temporarily shortly before the nine index point position, this opening occurring, however, before the cam contacts 17 close and terminating shortly after contacts 17 close.

Bearing this circuit arrangement in mind, the 55 operation may be most clearly understood from a specific example. The subscripts to the letters representing the brushes, counter and printer magnets and relays indicate the several denominational orders. Assume that a certain record card passing the brushes is punched to represent the nine complement 9949 in columns traversed by brushes LB₄, LB₃, LB₂ and LB₁, respectively, and that the true value 50 is to be printed. In 60 this event printer magnet S₁ must effect printing

of 0, printer magnet S₂ must effect printing of 5 and printing must be suppressed from printer magnets S₃ and S₄. As the nine index point position of the card arrives under the brushes an impulse is emitted for counter magnets Z₁, Z₃ and Z₄ but not for Z₂. Counter magnets Z₁, Z₃ and Z₄ therefore close their contacts s₁, s₃ and s₄ and establish circuits for the relays R₁, R₃ and R₄ whereupon contacts r₁, r₃ and r₄ open and contacts t₁, t₃ and t₄ close. Contacts r₂ remain closed 10 and contacts t₂ and s₂ remain open, as their corresponding counter magnet Z₂ has not yet received an energizing impulse.

The circuits of the relays R₁, R₃ and R₄ are completed through cam contacts 17 which, it will 15 be recalled, close in the nine position after contacts 16 have opened but before they close again. Contacts 16 now close while the nine index point position is still at the brushes and the effect is to energize printer magnet S₁ causing it to arrest 20 its printing bar in zero position. The circuit for the magnet S₁ extends as follows: through cam contacts 16, line 15, contacts r₂, line 21, contacts t₁, to printer magnet S₁, thence through contacts s₁, previously closed by the energization of counter 25 magnet Z₁, for the entry of nine on the counter, and thence to the other side of the line. The energization of the printer magnet S₁ in this case is made dependent on the non-energization of a relay R in a higher denominational order. 30 This non-energization depends, of course, on whether the higher denominational order printing magnet is to effect printing of a significant figure as that is the only case in which it receives no impulse in the nine index point position. The fact that contacts r₂ are closed when cam contacts 16 close has no effect on the printer magnet S₂ as the circuit of the latter is open at s₂. 35

In the case of printer magnets S₃ and S₄ there is no contact r left closed in the higher denominational orders to complete their circuits during the cycle and consequently they are not energized at all and their type bars rise to their highest position in which no type may print. It will be noted that several zeros in successive 40 denominational orders to the right of a significant figure may be printed as the closure of any contacts r provides a path for all lower denominational orders in which the contacts t are closed.

Later in the cycle, when brush LB₂ encounters 45 the perforation in the four index point position the magnet Z₂ will be energized to enter four on the counter. Incidentally contacts s₂ close to establish the circuit of printing magnet S₂ and the corresponding type bar stops with its "five" 50 type in printing position. Toward the end of the cycle after the several type have printed, the contacts s open in the usual manner. Thus at the beginning of each cycle of operation the machine circuits assume the condition shown in 55 Fig. 2.

A further example will now be explained. Assume the direct number 901 is to be printed, in which case the record card is perforated with the nines complement 9098 in columns traversed by 60 brushes LB₄, LB₃, LB₂ and LB₁, respectively. As the nine index point position of the card arrives at the brushes an impulse is emitted for counter magnets Z₄ and Z₂ causing closure of their related contacts s₄ and s₂. At this time contacts 17 are 65 closed and contacts 16 are open so that closure of contacts s₄ and s₂ will effect energization of their related relay magnets R₄ and R₂ causing closure of contacts t₄ and t₂ and opening of contacts r₄ and r₂. Closure of contacts 16 while contacts 17 70

are still closed will complete a circuit to energize printer magnet S_2 to interrupt the zero type at printing position in that order. This circuit is traceable from cam contacts 16, wire 15, contacts 5 t_3 , contacts t_2 , printer magnet S_2 , contacts s_2 , now closed, to left side of line. When the "8" perforation is analyzed by brush LB , the print magnet S_1 will be energized directly to select a "1" for printing and later magnet S_3 will be 10 similarly energized under control of brush LB_3 to select a "9" for printing. Thus at the end of the cycle the direct number 901 will be printed in response to the perforations 9098.

Having now explained the invention, what is 15 claimed is:

1. In an accounting machine, an automatic printing device comprising a plurality of movable type carriers each having a plurality of spaced type mounted thereon, a record card movable synchronously with said type carriers and having rows of index point positions, corresponding to the type spacing, card analyzing means, control devices adapted to be operated by said analyzing means in response to the analysis of a single row 20 of index point positions only and means controlled by said devices for controlling the operation of the carriers to print zeros selectively in the positions to the right of the highest order significant figure to be printed.
2. In an accounting machine, means for analyzing digit representing perforations in the columns of a record card in the order 9, 8,-0, printing mechanism in the order 0, 1---9, said card being movable synchronously with said printing 25 mechanism, means for controlling the operation of said printing mechanism for zero printing and means controlled by said analyzing means and operative upon analysis of the nine digit perfora- 30
- 35

tions for setting said controlling means to suppress the printing of zeros to the left of the highest order significant figure of the number to be printed.

3. In an accounting machine, means for analyzing perforations in a record in the order 9, 8,-0, said perforations representing by their location the complement of a number, a zero printing control device settable under control of said analyzing means in accordance with the occurrence of perforations representing nines, printing mechanism adapted to present type in the order 0, 1-9, a record card movable synchronously with said printing mechanism and means controlled by said control device for selecting zeros for 10 printing in certain orders of the number to be printed and for suppressing the printing of zeros in certain other orders.

4. The invention set forth in claim 3 in which the selection and suppression of zeros is effected 20 prior to the analysis of the digit representing perforations other than those representing nines.

5. In a machine of the class described, means for analyzing the index point positions of a record card for perforations representing the 25 complement of a number, printing mechanism controlled by said analyzing means to print the complementary value of the number analyzed, a record card movable synchronously with said printing mechanism, relays controlled by said analyzing means in response to perforations in the 30 card representing nines, and means controlled by said relays for controlling the operation of the printing mechanism to print zeros selectively to the right of the highest order in which no 35 nine perforation is present.

HERMANN ADALBERT WEINLICH.
